UNITED STATES PATENT OFFICE.

ARTHUR HERSCHEMANN, OF NEW YORK, N. Y., ASSIGNOR TO L. C. WEIR, OF SAME PLACE.

STEAM-GENERATOR.

SPECIFICATION forming part of Letters Patent No. 663,027, dated December 4, 1900.

Application filed February 23, 1900. Serial No. 6,146. (No model.)

To all whom it may concern:

Be it known that I, ARTHUR HERSCHEMANN, a subject of the Emperor of Austria-Hungary, residing at the city of New York, borough of 5 Manhattan, and State of New York, have invented certain new and useful Improvements in Steam-Generators, of which the following is a full, clear, and exact description.

This invention relates to steam-generators. 10 The object of the invention is to provide an apparatus of small dimensions and compact structure which will be capable of making steam rapidly and provided with features rendering it well adapted for use upon self- 15 propelled vehicles. Among the requirements of such a boiler may be mentioned the ability to get up steam quickly, small size for a given horse-power, and adaptability in shape for convenient disposition upon the vehicle. 20 The invention consists of the constructions and combinations hereinafter fully described, and particularly pointed out in the claim.

In the accompanying drawings, Figure 1 is a vertical section of my improved boiler, and 25 Fig. 2 is a horizontal section of the same on line xx of Fig. 1.

Referring to the drawings by letter, A represents the outer cylindrical shell, provided with the brackets a for supporting it on any 30 suitable framework. Inside of this shell is another shell B, constituting the fire and tube chamber. At the lower end of this chamber is the grate C, and the upper end is closed by a tube-sheet D, the center of which is open 35 to provide a passage for the fuel, which passage is formed by a short length of pipe d , passing from the tube-sheet upward through the center of the top of the outer shell, where it is closed by a cover d' . This cover is carried at the end of a lever e , which is pivoted 40 to the bracket e' , somewhat remote from the edge of the cover, so that when the cover is lifted for the admission of fuel by swinging the outer end of the lever downward it will 45 leave the entire opening clear.

The grate C is formed of two semicircular parts, with their diametrical sides parallel and hinged by means of rods c , resting in brackets c' . The parts of the grate are normally supported in the same horizontal plane 50 by latches c^2 , which engage angular projec-

tions c^3 from the edges of the grate-sections. By lifting these latches the two sections of the grate will swing downward toward each other and dump the contents of the grate. 55 No claim is made herein to this form of grate.

The tubes for the circulation of the water are indicated at f . They are vertical for the greater part of their length and are arranged in a nest in the fire-chamber, surrounding the 60 vertical axis thereof. The upper ends of the tubes project through the tube-sheet D, and their lower ends are curved outward immediately above the fire and pass laterally through the shell of the fire-chamber. The 65 water occupies the annular space between the two shells A B, the normal water-line being slightly above the tube-sheet D, the space above the water-line being for steam, as usual. Thus it will be seen that the tubes furnish 70 circulatory passages of great capacity which bring the water into close relation with the burning fuel.

For the purpose of distributing the heat throughout the entire nest of tubes I divide the 75 smoke-flue into two parts and connect them with the fire-chamber at the upper end thereof and at diametrically opposite points, as indicated at s and s' . In this way the products of combustion instead of being directed into 80 contact with the tubes on one side of the boiler are caused to make substantially equal contact with all the tubes. The two smoke-flues lead directly into a semicircular pipe s^2 , which embraces one-half of the exterior of 85 the boiler and connects with the base of the stack S, leading vertically upward at the rear of the boiler. This passage for the fuel is continued below the tube-sheet D by a coil of pipe G, extending nearly to the bed of fuel. 90 This coil, besides giving shape to the fuel-passage, also serves as a baffle to direct the heat and products of combustion toward the sides of the fire-chamber where the tubes are located, and it also serves as a superheating 95 device for the steam. For the last-mentioned purpose one end of the coil (indicated by g) leads upward through the fuel-passage d , then laterally outward, and finally to the steam-space of the boiler through the pipe g' . To 100 this pipe g' there is also connected a safety-valve h and a valve i , by which steam may

be cut off entirely from the coil G. The other end of the coil G (indicated by g^2) also leads upward through the fuel-passage and then by pipe g^3 to the engine or other steam-consuming apparatus. It will be seen that the supporting-coil exposes a large surface to the direct action of the heat and that the pressure of the steam passing through it from the steam-space will be materially increased.

10 Immediately surrounding the fire-space of the boiler, where it will be subjected to the greatest heat, I locate a hollow ring R, which communicates by means of the pipe r with the exhaust-passage of an engine. Another 15 pipe r' connects with the ring at a point diametrically opposite the pipe r and forms an exit to the atmosphere for the contents of the ring. The exhaust-steam from the engine, which ordinarily condenses the moment it 20 enters the atmosphere and becomes visible, is subjected to the intense heat of the fire in the boiler and is disintegrated the hydrogen and oxygen being so widely dissociated that when they finally exhaust to the atmosphere 25 they will not unite and form the usual visible vapor. A boiler with this attachment will

therefore eliminate the objectionable feature of the exhaust of the engine and is to that extent well adapted for use in a self-propelled vehicle.

30 While it has been stated that this boiler is specially adapted for self-propelled vehicles, it is to be understood that its use extends to all other conditions to which steam-boilers are applicable.

35 Having described my invention, I claim—

In a vertical steam-boiler, the combination of a fire-chamber provided with a nest of vertical tubes arranged in a circle around an axial fuel-passage, a cylindrical baffle in the 40 form of a coiled tube, lining the circular nest of tubes and giving shape to the fuel-passage, and two smoke-flues arranged at diametrically opposite points substantially as and for the purpose set forth.

45 In witness whereof I subscribe my signature in presence of two witnesses.

ARTHUR HERSCHEMANN.
